(57) **CLAIM**

The ornamental design for a wireless earphone, as shown and described.

DESCRIPTION

FIG. 1 is a front perspective view of a wireless earphone showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a circle portion 9 of FIG. 1; and,

FIG. 10 is an enlarged view of a circle portion 10 of FIG. 2. The broken lines in the drawing depict portions of the wireless earphone that form no part of the claimed design. The dot dash dot broken lines encircling portions of the wireless earphone in FIGS. 1, 2, 9, and 10 and illustrated in enlarged views, form no part of the claimed design.
